UNITED STATES PATENT OFFICE

JAMES E. FARRELL AND JOSEPH I. GASKILL, OF EASTHAMPTON, MASSACHUSETTS, ASSIGNEES TO WEST BOYLSTON MANUFACTURING COMPANY, OF EASTHAMPTON, MASSACHUSETTS, A CORPORATION OF MASSACHUSETTS

SEPARATOR FOR TWISTING AND SPINNING MACHINES

Application filed May 21, 1930. Serial No. 454,481.

This invention relates to separators for twisting and spinning machines and has for one of its objects to provide a novel separator which has special advantages when used in a twisting or spinning machine that is operated in such a way that the cord being twisted or the yarn being spun balloons to such an extent that adjacent balloons interfere with each other.

10 Our improved separator is so constructed as to permit of this excessive ballooning of the cord or yarn while preventing the adjacent balloons from interfering with each other. This end is secured by the construction of separator which allows adjacent balloons to overlap while maintaining them out of contact or engagement with each other.

We have illustrated the invention herein as applied to a ring twisting frame but we 20 wish to state that the invention is applicable to ring spinning frames or to any twisting or spinning frame which is being operated in such a way that the balloons formed about adjacent bobbins are apt to interfere with each other.

In the drawings, Fig. 1 is a sectional side elevation of a portion of a ring twisting frame equipped with our improved separators;

30 Fig. 2 is a top plan view of a portion of the frame;

Fig. 3 is a front view of Fig. 2;

In the drawings 1 indicates a frame portion of a ring twisting frame which is 35 equipped with a plurality of spindles 2. These spindles are mounted on the spindle rail 3 through the medium of usual bolsters 4 and each spindle is driven by a hand 5 which operates around a pulley 6 carried by the spindle.

7 indicates the ring rail carrying the spinning rings 8 on which are mounted the usual travelers 9.

45 10 indicate the usual rolls by which the strands to be twisted together to form the cord 11 or the sliver which is to be twisted into yarn are fed to the machine, and 12 indicates the usual guide eye situated above 50 the spindle and carried by the thread board

13 and through which the cord or yarn 11 passes to the traveler 9.

In the operation of twisting frames one of the factors which determines the size of the balloon which is formed is the weight of the traveler and other things being equal, the use of a lighter traveler will produce a greater ballooning effect, while the use of a heavier traveler will produce a lesser ballooning effect.

It is sometimes desirable to operate the twisting frame with a relatively light traveler which will normally result in increasing the size of the balloon around each bobin. These spinning frames are usually manufactured with the spindles situated a predetermined distance apart, which is a sort of standard distance for machines of this type, and if it is desired to operate the machine under such conditions as to produce an increased ballooning of the cord 11 the adjacent balloons are apt to engage each other thus causing either imperfection in the twisted cord or possibly causing breakage of the cord.

As stated above we have by our present invention provided a novel separator to be used between adjacent spindles which will permit the increased or extra ballooning of the cord 11 while preventing adjacent balloons from engaging each other.

Our improved separator is indicated at 15. This is made to have a considerable vertical dimension as well as the necessary dimension from front to rear. The separator herein shown is made of a piece of sheet metal which is shaped to present a concave card-engaging face 16 on one side and a convex card-engaging face 17 on the other side. The top and bottom edges 18 and 19 of each separator extend vertically in the same vertical plane situated midway between adjacent spindles but the intermediate portion is given a concavo-convex form in a vertical direction thereby to produce the concave face 16 and the convex face 17. While each separator has the concavo-convex form in the vertical direction yet it is straight in a horizontal direction. The concave face 16 and the convex face 17 thus have a nesting relation with the upper 20

and lower limits of the curved portion of each face occupying the same vertical plane.

The separator may be carried in any suitable or usual way. As herein shown each separator is provided at its rear edge with a stem portion 20 having a horizontally-extending foot portion 21 which is attached to the rail 22 through the medium of a suitable bolt 23.

10 The rail 22 is secured to bracket members 24 that are pivoted at 25 to standards 26 rising from the ring rail 7. The pivotal connection of the brackets 24 with the standards 26 permit the rail 23 with the separators thereon to be swung backwardly for 15 removing or replacing the bobbins.

The manner in which the separators function will perhaps be best seen from Fig. 3. The balloon formed by two adjacent cords 11a and 11b for instance, Fig. 3, will engage 20 the opposite sides of the separator between corresponding bobbins and as shown in Fig. 3 the balloon of cord 11a will engage the concave face 16 of said separator while the balloon formed by cord 11b will engage 25 the convex face 17 of said separator. The portion of the cord 11a which engages the concave face 16 of the separator overlaps the portions of the cord 11b that are situated 30 adjacent the top and bottom edges of the separator but these overlapping portions are held out of contact with each other by means of the separator. This particular separator with the opposite faces having a nesting relation thus not only prevents the balloons 35 from lashing each other but it also allows the increased ballooning effect to take place.

The increased size of the balloon formed in the cord 11a for instance may be accommodated by the concave face 16 of the separator while the convex face 17 accommodates the extra length of the cord 11b between the traveler and guide eye 12 which is occasioned by the increased ballooning 40 effect. In other words, with our improved separator each balloon is allowed to have a sufficient size so that it would normally interfere with an adjacent balloon and the portions of two adjacent balloons, which 45 might normally interfere with each other, are maintained out of contact with each other but in overlapping relation.

We claim:

1. In a ring twisting frame, in combination with a plurality of spindles, bobbins carried thereby, and means to twist cords and wind them on the bobbins, of a separator between each two adjacent spindles, one face of each separator with which the 55 cord to be wound on one bobbin engages being concave in a vertical direction and the opposite face of the separator with which the cord wound on an adjacent bobbin engages being convex in a vertical direction, 60 said faces, both being straight in a horizontal 65 direction and having a nesting relation and the top and bottom edges of each separator being in the same vertical plane situated midway between the adjacent spindles.

70 2. In a ring-twisting frame, in combination, a plurality of spindles, bobbins carried thereby, a spinning ring and traveller for each spindle by which cords are twisted and wound on the bobbins, a separator between each two adjacent spindles, each separator 75 being straight in a horizontal direction and having at its upper and lower edges a vertically-extending portion situated in the same vertical plane midway between the adjacent spindles, and the central portion of each separator having a concavo-convex shape in a vertical direction.

80 In testimony whereof, we have signed our names to this specification.

85 JAMES E. FARRELL.
JOSEPH I. GASKILL.
